UNITED STATES PATENT OFFICE.

GUY F. REESE, OF FAIRMOUNT, ILLINOIS, ASSIGNOR OF ONE-HALF TO A. E. CROMWELL
AND ONE-HALF TO J. O. SMITH, OF FAIRMOUNT, ILLINOIS.

TRAMMEL.

1,031,198.

Specification of Letters Patent.

Patented July 2, 1912.

Application filed November 19, 1910. Serial No. 593,267.

To all whom it may concern:

Be it known that I, GUY F. REESE, a citizen of the United States, residing at Fairmount, in the county of Vermilion and State 5 of Illinois, have invented certain new and useful Improvements in Trammels, of which the following is a specification, reference being had therein to the accompanying drawing.

10 This invention relates to trammels and the principal object of the same is to produce an improved form of trammel arranged to operate upon a pitman so that the latter will be moved backward and forward twice 15 to each revolution of the trammel.

This invention is illustrated in the accompanying drawings wherein:

Figure 1 is a perspective view of the operating wheel and pitman. Fig. 2 is a top 20 plan view of the operating wheel showing how the same is mounted upon the machine. Fig. 3 is a view of one of the sliding blocks. Fig. 4 is a transverse sectional view through the sliding block. Fig. 5 is a perspective 25 view of one of the plates secured to the driving wheel.

Referring to the accompanying drawings by numerals it will be seen that the invention comprises a circular disk 1 which is 30 made of any desired metal—such as iron or steel—and is journaled to the frame 2 within the socket piece 3. The disk has secured to its outer surface a substantially X-shaped path way, which is composed of a number 35 of plates 4 and 5. The plates 4 are of greater length than the plates 5 and have their ends flush with the inner edges of the shorter plates 5. The plates are spaced apart to provide path ways 6 and are provided with the over-hanging flanges 7 between which there is left a narrow slot. A 40 pair of blocks having a rectangular lower portion 8 and an upstanding longitudinal lug 9 are placed within the path ways, the 45 rectangular portion 8 fitting within the path way 6 and the lug 9 fitting between the flanges 7. Each of the blocks is provided with a centrally located vertical opening 10

which is provided at its inner end with an enlarged portion 11. A bolt 12 is passed 50 through the opening 10 and has its head countersunk within the enlarged portion 11 so that it will not project and thus interfere with the movement of the blocks.

A pitman 13 is provided near its end with 55 a pair of openings through which the bolts 12 pass and the pitman is retained upon the bolts by means of the pins 14 which pass through the openings 15 formed in the outer end of the bolts. 60

In the operation of the device, the disk 1 is rotated and as it rotates the blocks slide back and forth through the path ways 6 and cause the pitman to reciprocate. As the pitman moves backward and forward, the pressure 65 comes against the plates 4 and 5 and by having the plates 4 longer than the plates 5, the end portions of the plates 4 are braced so that there is no danger of the pitman working them loose from the securing bolts 70 16. When the pressure comes against the longer plates there is also no danger of them becoming loose as the pressure comes against the longitudinal diameter and as the block is in contact with the end portion of the 75 plate 4 which is next to it and which is braced by its abutting plate 5, there is formed a very strong device.

Having described the invention, I claim:

A trammel comprising a rotary disk having 80 an unbroken outer face, and pairs of right angularly disposed strips mounted upon the outer face of said disk and forming a substantially X-shaped path, each pair of strips comprising a short strip of the 85 same width throughout its entire length and a long strip of the same width throughout its entire length and overlapping the end of said short strip and having its end flush with the side of said short strip. 90

In testimony whereof I hereunto affix my signature in presence of two witnesses.

GUY F. REESE.

Witnesses:

JOHN KEENE,
I. M. BUSBY.
